Primary Examiner — Elizabeth Albert(74) *Attorney, Agent, or Firm* — David I. Roche; Baker & McKenzie LLP(57) **CLAIM**

The ornamental design for a writing instrument, as shown and described.

DESCRIPTION

FIG. 1 is a perspective view showing my new design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The broken line in FIG. 6 is included for the purpose of showing a portion of the writing instrument that forms no part of the claimed design.
